UNITED STATES PATENT OFFICE.

SILAS I. ATWATER, OF NEW YORK, N. Y.

TABLET.

1,006,711.

Specification of Letters Patent. Patented Oct. 24, 1911.

Application filed January 14, 1911. Serial No. 602,667.

To all whom it may concern:

Be it known that I, SILAS I. ATWATER, a citizen of the United States, residing at New York city, in the county of New York and State of New York, have invented certain new and useful Improvements in Tablets, of which the following is a specification, reference being had therein to the accompanying drawing.

10 My invention relates to improvements in tablets and more particularly has reference to writing tablets or attachments especially adapted for use in combination with telephones.

15 In the preferred form in which I have illustrated my invention the tablet comprises a bed or table in combination with a suitable roll of paper which may be torn off as used and the invention contemplates certain means for holding the roll of paper in position and for applying tension to the same.

20 Referring to the accompanying drawings, Figure 1 is a perspective view of a suitable tablet illustrating an application of my invention and showing the roll of paper held away from the table for clearness. Fig. 2 is a plan view looking downwardly at the same, also showing a suitable clamping device for attaching the tablet to the telephone standard. Fig. 3 is a longitudinal section on the line 3—3 of Fig. 1 and Fig. 4 is a plan view of a carbon paper attachment.

25 4 is the table or bed of the tablet which is preferably provided with the slots 5 and 6 and which may be curved to form a shield or apron such as 7 to cover the roll of paper 8 at the lower portion of the same.

30 40 9 and 10 are flanges or lugs preferably turned up from the body of the table or bed to keep the roll of paper in position.

35 45 11 is a bracket which may be secured to the table or bed 4 by rivets or other suitable means as shown. This bracket is preferably provided with lugs or off-sets 12 and 13 and may also be drilled and tapped at the outer extremity to receive the screws retaining the cap or clamp 14 for securing 50 the bracket in position upon the standard of the telephone.

40 45 55 15 is a spring or other resilient member preferably of substantially the shape shown of a suitable width to enable the sides thereof to be engaged beneath the lugs 12 and 13 as shown, the lower extremities being

laterally extended in the direction of each other to engage the core 16 of the roll of paper as shown thus serving as an axis or support for the roll of paper and at the same time bearing against the under surface or face of the bed or table of the tablet to apply tension to the paper 17 when in position.

50 In assembling the device the tablet is bound to the standard of the telephone by 65 the clamp 14, the roll of paper is then mounted in the lower extremities of the resilient member 15 as shown, and the end of the roll of paper is passed through the slot 6 over the upper face of the table or bed 4, 70 passing downwardly through the upper slot 5 over the resilient member 15 which bears against the paper, pressing it against the under surface of the bed 4. The tension of the spring 15 causes the roll of paper to 75 bear slightly against the under face of the bed, and the other end of the spring 15 also causing the paper to bear against the under face of the bed, leaves sufficient tension to hold the paper in position to write 80 upon and enables the same to be pulled through and torn off as desired.

85 The paper may be rolled double, that is to say, two strips may be wound upon the same roll for the purpose of making carbon or duplicate copies of memoranda. In that case the carbon sheet 18 shown in Fig. 4 as secured in the bar 19, may be inserted between the strips of the roll by securing the bar 19 to the bed 4 in any suitable manner 90 as by the wing nuts 20—20a.

95 Of course it will be readily understood that the carbon sheets such as 18 may be removed from the bar 19 and replaced with new sheets from time to time and it will also be understood that a roll of a single strip of paper may be used thus eliminating the use of the carbon sheet entirely. It will also be understood that various modifications may be made in the general construction and arrangement of the apparatus without departing from the spirit of the invention as set forth in the claims.

I claim:

1. In a tablet, a table, a holder secured 105 intermediate of the ends of said table, said holder being formed of a single piece of wire bent to bear against the under side of said table at one end, the free end portions terminating in offsets to engage a roll at 110 the other end of said table, said holder located entirely beneath said table.

2. In a tablet, a table, a holder secured thereto, said holder being formed of a single piece of wire bent to bear against the under side of said table at one end, the free end portions terminating in offsets to engage a roll at the other end of said table, said plate having an apron formed integrally therewith and adapted to cover said roll.
3. In a tablet, a table, a holder secured thereto, said holder being formed of a single piece of wire bent to bear against the under side of said table at one end, the free end portions terminating in offsets to engage a roll at the other end of said table, said plate having slots at opposite ends thereof through which the paper of said roll may pass.
4. In a tablet, a table, a holder secured thereto, said holder being formed of a single piece of wire bent to bear against the under

side of said table at one end, the free end portions terminating in offsets to engage a roll at the other end of said table, and said plate provided with projections adjacent to the sides of said roll.

25

5. In a tablet, a table, a holder secured thereto, said holder being formed of a single piece of wire bent to bear against the under side of said table at one end, the free end portions terminating in offsets to engage a roll at the other end of said table, and detachable means for securing a piece of transfer paper to said plate.

In testimony whereof I affix my signature in presence of two witnesses.

SILAS I. ATWATER.

Witnesses:
